UNITED STATES PATENT OFFICE.

JOHN S. DRISCOLL, OF BOSTON, MASSACHUSETTS.

COMBINED ASH RECEPTACLE AND CIGAR HOLDER.

Application filed December 11, 1923. Serial No. 679,908.

To all whom it may concern:

Be it known that I, JOHN S. DRISCOLL, of Boston, in the county of Suffolk and State of Massachusetts, have invented certain new and useful Improvements in Combined Ash Receptacles and Cigar Holders, of which the following is a specification.

My invention relates to combined ash receptacles and cigar holders and it has for its object to provide an improved article of this kind. It is also an object of my invention to provide, as a new article of manufacture, a combined ash receptacle and cigar holder attachment for automobiles which will be attractive, simple in construction and efficient, and which will possess features of construction rendering the device particularly adapted to that special use.

To these ends my invention consists of a combined ash receptacle and cigar holder having the novel and advantageous features of construction and arrangement of parts set forth in the following description and particularly pointed out and defined in the claims at the close thereof.

In the accompanying drawings:

Figure 1 is a front elevation of a combined ash receptacle and cigar holder constructed in accordance with my invention.

Figure 2 is a section on line 2—2 of Fig. 1.

Figure 3 is a plan view of the receptacle-holder shown in Figs. 1 and 2, but showing the lid, hereinafter described, in its closed position.

Figure 4 is a rear elevation of the receptacle-holder shown in Figs. 1 and 2.

Figures 5 and 6 are details of the bracket hereinafter described.

Figure 7 is a sectional plan view illustrating a modification.

Figure 8 is a sectional detail, hereinafter described, relating to the modification shown in Fig. 7.

Having reference to the drawings, 1 represents a metal box constructed with a flat perpendicular rear wall 2 that is formed with a pair of vertically disposed button-hole slots 3, 3 to receive a pair of buttons or studs 4, 4 projecting from a plate 5 secured by screws 6 to any suitable supporting fixture 7. Each button or stud 4 is made with a relatively large head connected with the plate 5 by a shank 8. The lower end portions of the slots 3 are enlarged to provide gateways for the heads of the buttons or studs, while the upper end portions of these

slots are just wide enough to accommodate the shanks of the buttons or studs. It will thus be clear that the box 1 is applied to the supporting bracket constituted by the plate 5 with its studs 4, by passing the heads of the studs through the enlarged lower ends of the slots and then lowering the box until the upper ends of the slots 3 rest upon the shanks of the studs. When thus applied to the supporting bracket the box 1 is both supported by the bracket and held against lateral or swinging movement relatively thereto in any direction.

In order to positively secure the box 1 against upward movement relatively to the bracket plate 5 I provide a leaf spring latch 9 fastened near its lower end to the rear wall 2 by rivets 10 and having its upper end disposed so as to occupy a position immediately under the heads of the studs 4 when the latter are at the upper ends of the slots 3. The spring latch 9 is under stress so as to yieldingly press toward the rear wall 2. Therefore, when the buttons or studs 4 are passed into the lower ends of the button-hole slots 3—3, the upper end of the spring latch 9 is first bent inwardly and then when the box 1 is slid downwardly on the studs 4 and the latter assume a position above the latch, said latch snaps into position below the studs as shown in Fig. 2, and serves to lock the box against upward movement relatively to the studs.

The box 1 is made with a fixed top wall section 11 through which loosely extends a stem 12 provided at its upper end with a thumb piece 13 and having its lower end secured to a cam or wedge block 14 whose lower end is quite thin and occupies a position between the upper end of the spring latch 9 and the rear wall 2. Downward movement of the wedge block 14 effected by finger pressure upon the stem 12 forces the upper end of the spring latch away from the rear wall 2 and out of engagement with the studs 4, thus leaving the box 1 free to be lifted and removed from the studs 4. As will be seen from Fig. 1, the cam block 14 is disposed between the two slots 3, 3 so as to engage the middle or intermediate portion of the upper end of the spring latch. When the box 1 is applied to the studs 4 the spring latch yields to permit the entrance of the studs into the enlarged lower ends of the slots 3, and then when the box is slid downward on the studs the spring

latch snaps into position beneath the heads of the studs, if the cam block 14 occupies its uppermost position, or will do so when the cam block is lifted by means of the stem 12. 5 Preferably the cam block 14 is so constructed that it must be manually lowered and manually raised.

A movable top wall section, or lid, 15 is provided, connected by a hinge 16 with the 10 fixed top wall section 11 so that it can be closed down on to the top of the box, as shown in Figs. 3 and 4, or set in an upstanding position as shown in Figs. 1 and 2, the hinge 16 preferably being stiff jointed 15 enough to hold the lid 15 in either position. Upon the inner side of the lid is fastened, as by rivets 17, a sheet metal bracket 18 formed with a pair of arms 19 made at their ends with eyes 20 within which are journaled trunnions provided at opposite sides of a detent arm 23 whose inner end is in engagement with a spring tang 21 that is part of the bracket 18. The trunnions 24 of the 20 detent arm 23 are located a short distance 25 away from the inner end of said arm so that the pressure of the spring tang 21 serves to hold said arm 23 in either extreme position or in its middle position shown in Figs. 1 and 2. The bracket 18 is also made with 30 a shelf 22, and when a cigar or cigarette is placed thereon as indicated by dotted lines in Fig. 2, the detent arm 23 may be swung down against it and serves to hold the cigar or cigarette against displacement. As will 35 be clear the shelf 22 supports the cigar or cigarette in a position directly above the open top of the box 1 so that ashes falling therefrom drop into said box.

When the receptacle-holder is not in use the lid 15 will be placed in its closed position so that not only are the parts carried by the lid then housed within the box, but the ashes within the latter cannot be blown out.

In the modification shown in Figs. 7 and 8 the rear wall 2^a of the box 1 is made with a pair of circular apertures 24 to receive the studs 4 and the box is locked in engagement with said studs by a slide 9^a that is yieldingly urged endwise in one direction, toward one side of the box, by a spring 9^b riveted to the side of the box. The slide 9^a is constructed with a pair of horizontally disposed button-hole slots 25 and the spring 9^b normally holds the slide in a position where the relatively narrow ends of the slots register with the apertures 24 and engage the studs 4. In one side of the box is slidably mounted a push button 26 and by manually pushing inwardly upon the same the slide 9^a may be shoved over against the opposite side of the box to bring the enlarged ends of the slots 25 opposite the apertures 24 and the heads of the studs 4. When the slide occupies this last described posi-

tion the box 1 may be placed on to or removed from the studs, and when in its normal position it serves to lock the studs in the apertures 24. A headed stud 27 projecting from the rear wall 2^a of the box and 70 occupying a slot 28 formed in the slide, cooperates with the top wall section to hold the slide against displacement except for limited endwise movement as described.

The above described ash receptacle and 75 cigar holder is particularly designed for use as an attachment for an automobile in which case the plate 5 may be fastened by the screws 6 to the back of the front seat, to the instrument board, or to any other part 80 of the vehicle desired.

What I claim is:

1. An article of the character described comprising a box provided with a hinged lid adapted to occupy an open upstanding position; a shelf upon the inner side of said lid for supporting a cigar or the like directly above said box when the lid is in its open position; a bracket adapted to be permanently attached to a supporting fixture; means 85 separably connecting said box and bracket, and a manually operated latch normally locking said box and bracket against separation.

2. An article of the character described 95 comprising a box having a vertical rear wall formed with a button-hole slot; a box-supporting fixture provided with a stud having a head adapted to be passed through the large end of said slot; a spring detent 100 mounted on said box and engaging the stud to hold the latter at the small end of said slot, and a cover hinged to said box provided upon its inner side with means for holding a cigar or the like directly above 105 said box.

3. An article of the character described comprising a box having a vertical rear wall formed with a pair of button-hole slots; a box-supporting fixture provided with a 110 pair of studs each having a head adapted to be passed through the large end of one of said slots; a spring detent mounted on said box and engaging both of said studs to hold the latter at the small ends of said slots; a cover hinged to said box provided upon its inner side with means for holding a cigar or the like, and a manually operated cam mounted on said box for operating said detent.

4. An article of the character described comprising a box having a vertical rear wall formed with a pair of button-hole slots; a box-supporting fixture provided with a 115 pair of studs each having a head adapted to be passed through the large end of one of said slots; a spring detent mounted upon the inner side of said wall and engaging both of said studs to hold the latter at the small ends of said slots; means operable manually 120

from the exterior of the box for operating said detent to free the studs, and a cover hinged to said box and provided upon its inner side with means for holding a cigar or the like.

5. In an article of the character described the combination of a box for holding ashes; means for holding a cigar or the like in position above said box; a supporting fixture for said box provided with a stud made with a head, said stud separably engaging a button-hole slot formed in a mem-

ber that is part of the box; a locking member movably mounted on said box and engaging said stud to hold the latter in engagement with said slot but movable relatively to the box to free the stud so that the box can be disengaged therefrom; a hinged cover on said box, and means upon the inner side of said cover for holding a cigar or the like. 15

In testimony whereof I have affixed my signature.

JOHN S. DRISCOLL.
